I. BERLINER ET AL
TRAIN TELEPHONIC APPARATUS

1,791,487

Filed Dec. 18, 1929

UNITED STATES PATENT OFFICE

ISIDOR BERLINER AND SAMUEL BERLINER, OF NEW YORK, N. Y.

TRAIN TELEPHONIC APPARATUS

Application filed December 18, 1929. Serial No. 414,867.

Our invention relates to improvements in train telephonic apparatus and the object of the invention is to provide a simple apparatus adaptable for use on railroads wherein telephonic communication can be established between stations, between station and train, between train and train, no matter whether the trains are on the same track or on different tracks and irrespective of the direction in which they are proceeding, and between a central exchange and a train, whether moving or stationary.

A further object is to provide, in addition, telephonic inter-communication in a train between the respective coaches and the cab of the engine.

Our invention consists essentially in the following arrangement and construction as hereinafter more particularly explained by the following specification and illustrated in the drawing in which:—

Fig. 1 represents a diagrammatic view of our system showing the same applied to a double track railroad line, two stations being indicated.

Fig. 2 is a vertical cross sectional view of a railroad truck showing an axle constructed according to our invention, mounted in bearings which are insulated from the journal boxes, and also the connections to the train circuit.

Fig. 3 is a vertical section through the line 3—3 Figure 2.

Fig. 4 is a sectional view through the coupling between the divided portions of the axle showing the means for insulating these two portions from each other, and

Fig. 5 is a section similar to Figure 2, illustrating a modified means for connecting the train telephone circuit to the wheel axle.

Like characters of reference indicate corresponding parts in the different views.

1, 1 and 2, 2 are the rails of the respective tracks, the sections of the rail 1, 1 and 2, 2 being insulated from adjacent sections. 3, 3 and 4, 4 are line wires paralleling the tracks and which may be strung along poles, or otherwise mounted, being connected to the respective station telephones 5, 5 by the wires 6, 6. Line wires 7, 7 may also extend be-

tween the respective station telephones 5, 5 and in addition wires 8, 8 may be connected in circuit, such wires 8, 8 extending to central telephone exchanges. The line wires 3, 3 are also provided with bridging wires 9 and 10 connecting such wires to the respective rails 1, 1 of each track, and further bridging wires 11 and 12 connect the line wires 4, 4 to the respective rails 2, 2 of the other track.

In Figure 1 in dotted lines are shown three trains, two on one track and one on the other, the coaches being indicated by 13 and the cabs of the engines by 14. 15 are the train telephones which are preferably located one in each coach and one in the cab 14 of the locomotive. 16 are the wires of the train telephonic circuit provided with connectors 17 between the engine and following coach, and between successive coaches, said telephones 15 being in circuit with the wires 16 and such wires being connected to the divided portions 18 of a single car axle in a manner which will hereinafter appear.

As illustrated in Figures 2, 4 and 5 of the drawing the divided axle portions 18 are secured together by means of the coupling portions 19, which are insulated from each other through the medium of the insulating disc 20, said axle portions 18 carrying the wheels 21 constructed and mounted on the axle portions in the orthodox manner. The outer ends of the axle portions 18 are received in the bearing rings 20 which are insulated from the journal boxes 23 through the medium of the insulating rings 24.

In the construction illustrated in Figures 2 and 3 the means of connecting the terminal ends of the train telephonic circuit wires 16 to the axle portions 18 is through rods 25 which are insulated from the truck frame 26, said rods being connected to the gear frames 27, each of which carries a gear 28 meshing with a gear 29 on the corresponding axle portion 18.

In the modified construction illustrated in Figure 5 instead of the connection between the terminals of the wires 16 and the axle portions 18 being constructed as illustrated in Figures 2 and 3, lead wires 30, each connected at one end to a wire 16 and

at the other to the metallic axle bearing 22, are provided.

Bridging wires 31 extend between the line wires 3, 3 and 4, 4 so that the circuit may be completed through the rails 2, 2 and the train circuits of the trains on such track.

For sake of clarity the various instruments and batteries in the telephone circuits have not been shown as these will be standard, well known to any one skilled in the particular art to which this invention appertains.

If reference is made to our previous United States Patent #1,350,291, the respective circuits are shown in detail and need not be repeated here.

Upon referring to Figure 1 it will be seen that communication can be established between any station 5 and the telephones 15 of any train. Likewise, communication can be established between a subscriber to a central exchange connected to the wires 8, 8 and any telephone in a train. In addition, intercommunication can be had between the cab of the engine and any coach in the train, or vice versa. We preferably provide our split axle on the end coach of a train, it being understood that only one axle for each train need be constructed in this special manner, the remaining axles being of standard construction.

The uses to which our apparatus may be put are very numerous, the most important among them is that train despatching can be done by telephone direct to the engine of the train concerned or to any selected telephone thereon.

The system will operate no matter whether the trains are stationary or moving and quite irrespective of the speed of the train.

As above described the circuit is completed through two wheels and axle portions metallically connected thereto there being no necessity of any further contact between rails and train.

Furthermore, the fact that intercommunication is established between the respective coaches and the engine is of great advantage, enabling conductors and train men to get in touch with the engine driver or fireman, or vice versa.

It is to be understood that this apparatus will preferably operate on the Bell telephone system, and switchboards for connecting any desired phone to any other desired phone will be included in the installation.

Such switchboards have not been shown as they form no part of the present invention.

What we claim as our invention is:

1. In a train dispatching telephone system, the combination with a plural rail track and a train movable thereon, said train having a wheeled truck provided with an axle consisting of sections disposed in endwise relation to each other, coupling means insulating said sections from each other, wheels on said axle, a telephone on said car, an in-

put wire connected to one terminal of the telephone, an output wire connected to the other terminal of the telephone, a collector ring on each section of the axle, and a brush engaging each collector ring and connected to one of said wires, whereby the input and output wires will be in circuit with the track rails to a distant telephonic apparatus placed in circuit therewith.

2. The combination set forth in claim 1, with the addition of a gear on each axle section, a frame mounted thereon, a second gear on the frame in mesh with the first gear, and a wire connected to said frame.

ISIDOR BERLINER.
SAMUEL BERLINER.
